[57] **CLAIM**

The ornamental design for a decorative surface for the edge portion of a plate, as shown and described.

DESCRIPTION

FIG. 1 is a front view of a decorative surface for the edge portion of a plate showing my new design;

FIG. 2 is an enlarged front view of FIG. 1 partially broken away for ease of illustration; and,

FIG. 3 is a front view of a decorative surface for the edge portion of a plate showing a second embodiment of my new design.

The broken lines shown in the drawing are for illustrative purposes only and forms no part of the claimed design.
